(57) **CLAIM**

The ornamental design for a graduated dispensing cap, as shown and described.

DESCRIPTION

FIG. 1 is a perspective view of a graduated dispensing cap.

FIG. 2 is a top plan view of the graduated dispensing cap of FIG. 1.

FIG. 3 is a front elevational view of the graduated dispensing cap of FIG. 1.

FIG. 4 is a rear elevational view of the graduated dispensing cap of FIG. 1.

FIG. 5 is a right-side elevational view of the graduated dispensing cap of FIG. 1; and,

FIG. 6 is a left-side elevational view of the graduated dispensing cap of FIG. 1.

The broken lines in the figures immediately adjacent to the shaded areas represent the bounds of the claim and form no part of the claimed design. The broken lines showing the structure of the handle portion and the connector portion of the graduated dispensing cap depict environmental only and form no part of the claimed design.
